GLOVE

Irwin Steinberger, New York, N. Y., assignor to
 Steinberger Bros. Glove Corporation, New York,
 N. Y., a corporation of California

Application September 26, 1933, Serial No. 691,045

3 Claims. (Cl. 2—165)

This invention relates to gloves and has for an object to provide an improved construction wherein not only an extra strong glove is presented, but one that has a pleasing outline.

Another object of the invention is to provide a glove with a binding formation along each seam which strengthens and at the same time ornaments the seam.

A further object, more specifically, is to provide in a glove a binding and a seam structure which covers and protects the usual over seam while providing a wearing surface and a reinforcing seam adjacent the over seam.

In the accompanying drawing—

Figure 1 is a plan view of a glove disclosing an embodiment of the invention;

Figure 2 is a fragmentary portion of one of the fingers of the glove shown in Figure 1; the same being on a large scale, with part of the trimming of the protecting strip disengaged and moved to one side for illustrating the position of the parts;

Figure 3 is a sectional view through Figure 1 approximately on the line 3—3, the same being on an appreciably enlarged scale.

Referring to the accompanying drawing by numerals, 1 indicates the glove body having the usual thumb 2 and the usual fingers 3, as far as the general arrangement is concerned. Heretofore in making gloves of this kind over seams were used at the various parts of the glove, and sometimes other formations of seams. In the present invention, however, instead of forming an over seam and then turning the fingers or other parts of the glove, there is provided an over seam 4 at the various places where seams are necessary and then on top of this seam there is provided a binding or covering member 5 which protects this seam, strengthens the parts 40 along the seams and also presents a pleasing appearance.

The seam structure is shown more specifically in Figures 2 and 3. It will be noted from Figure 3 that the fourchettes 6 and 7 are arranged with the sections 8 and 9 near their adjacent edges positioned to fit flatwise against each other so as to receive the over seam 4. The same structure is true of the other edges of the remaining fourchettes. As illustrated in the upper right hand corner of Figure 2 there is provided a binding or covering strip 5 with a portion 5' fitting against the section 8. When the parts are substantially in this position the over seam 4 is applied, as shown at the bottom right hand corner in Fig. 3. This will con-

nect all the sections 5, 5', 8 and 9 together. It will be understood that this seam 4 is on the outside of the glove and the glove is not turned after the seam has been made. After the seam 4 has been added, as shown in the lower left hand corner of Fig. 3, the binding 5 is turned over as shown at the lower left hand corner in Fig. 3, and a line of stitching 10 is applied. For the purpose of description this line of stitching is known as the "aris" stitching and extends through sections 8 and 9 and through the binding 5 near the free edge 11. This line of stitching is drawn in rather tightly so that the edge 11 is sunk into the structure and thereby leaves a round formation presenting the desired form of binding and reinforcing structure. The binding protects the over seam 4 and thereby provides a greater wearing action. This structure also permits the glove to be properly manufactured without the necessity of turning. It will be observed that the binding 5 is sewn rather loosely as shown at the lower left hand corner of Fig. 3 but this is for the purpose of illustration only, as in the actual manufacture of the glove the covering or binding member 5 is drawn down as tightly as possible before the aris seam 10 is applied.

It will also be noted that the edge 11 exposes a very small amount of the interior surface of the leather and that this is usually of a different color from the outer surface. Thus there is presented an almost hairline of color adjacent the seam which adds to the pleasing appearance of the completed glove without the necessity of adding any special trimming thereto.

I claim:

1. A glove comprising a body merging into fingers and a thumb, each of said fingers and the thumb being provided with an over seam for connecting adjacent parts near their outer edges, a binding member having one edge portion secured in place by said over seam, said binding member being fitted over the over seam and adjacent parts of the glove, and an aris seam extending through the other edge portion of the binding member and through adjacent parts of the glove for securing the second edge of the binding member in place.

2. In a glove of the character described, a seam for connecting adjacent parts together, a covering member straddling said adjacent parts with said seam extending through said adjacent parts and one edge portion only of the covering member, and a second seam extending

through said adjacent parts and the other edge portion only of said covering member for clamping the covering member in position, whereby most of it straddles the first mentioned seam and straddles adjacent parts of the glove held together by the first mentioned seam.

3. In a glove of the character described, means for connecting adjacent edges of certain parts of the glove together, said means including a binding strip, an over seam extending through part of the binding strip and through adjacent edges of the glove, said over seam bind-

ing the three parts firmly together with the bound part arranged exteriorly of the glove, and a second seam extending through the opposite edge of said binding member and through said adjacent edges of the glove for securing said second edge in place whereby the binding member is maintained in a straddling position over adjacent edges of the glove and most of the over seam for strengthening the glove and protecting the over seam.
